US00D526617S

(12) **United States Design Patent** (10) **Patent No.:** **US D526,617 S**
Yamane et al. (45) **Date of Patent:** **** Aug. 15, 2006**

(54) **CONNECTOR**

(75) Inventors: **Hiroshi Yamane**, Kanagawa (JP);
Junya Kajimoto, Kanagawa (JP)

(73) Assignee: **J.S.T. Mfg. Co., Ltd.**, Osaka (JP)

(**) Term: **14 Years**

(21) Appl. No.: **29/183,060**

(22) Filed: **Aug. 21, 2003**

(30) **Foreign Application Priority Data**

Dec. 6, 2002 (JP) 2002-033992

(51) **LOC (8) Cl.** **13-03**

(52) **U.S. Cl.** **D13/147**

(58) **Field of Classification Search** D13/147;
439/260, 325, 329, 492, 495, 570, 607

See application file for complete search history.
